LIFTING JACK

Millard B. Lucker, St. Joseph, Mich., assignor to
 Auto Specialties Manufacturing Company, St.
 Joseph, Mich., a corporation of Michigan

Application December 14, 1939, Serial No. 309,139

16 Claims. (Cl. 254—106)

This invention relates to lifting jacks, and particularly to jacks of the friction gripping clamp or cam type.

It is an object of the invention to provide a lifting jack of the friction clamp or cam type which is of improved construction and operating characteristics.

More particularly, it is an object of the invention to provide a friction clamp or cam lifting jack wherein the jack load-lifting member may be operated in predetermined step increments of movement both during load-raising and load-lowering operations.

A further object of the invention is to provide a friction clamp or cam type lifting jack wherein the load-lifting member may be raised or lowered in predetermined step increments of movement and wherein the load-lifting member and the load supported thereby are at all times under positive and accurate control insuring uniformity and safety in the operation of the jack device. In accordance with the invention the jack construction is provided with actuating and holding friction clamps or cams, and means is provided for automatically shifting the weight of the load from one to the other of the clamps during load-raising and lowering operations, at least one clamp being at all times operative to support and maintain control of the load movements.

A still further object of the invention is to provide a friction clamp or cam type lifting jack wherein the load may be raised or lowered in predetermined step increments of movement by the manipulation of a single operating lever, conditioning or control means being provided for determining the direction in which the load-lifting member will be moved as the lever is actuated.

Various other objects, advantages and features of the invention will appear from the following specification when taken in connection with the accompanying drawings, wherein a preferred embodiment of the invention is set forth for purposes of illustration.

In the drawings, wherein like reference numerals refer to like parts throughout:

Fig. 1 is a general side assembly view of a lifting jack constructed in accordance with one preferred form of the invention.

Fig. 2 is a front sectional view of the jack structure shown in Fig. 1, on the line 2—2 thereof, particularly illustrating the internal construction of the lifting body and its associated parts. The structure is illustrated as conditioned for load-raising operations.

Fig. 3 is a view generally similar to Fig. 2,

but showing the structure as conditioned for load-lowering operations.

Figs. 4 and 5 are transverse sectional views of the structure of Fig. 1, taken on the lines 4—4 and 5—5 respectively thereof.

Fig. 6 is a detail perspective view of the main lifting body.

Fig. 7 is a detail perspective of the auxiliary frame adapted to be associated with the main frame or lifting body.

Fig. 8 is a detail perspective of the operating lever.

Fig. 9 is a side sectional view of the structure of Fig. 1, more particularly illustrating the internal operating mechanism, and

Figs. 10 to 14 inclusive are views generally similar to Fig. 9 but showing various operating positions of the mechanism. Figs. 9 and 10 show the structure during load-raising operations, and Figs. 11, 12, 13 and 14 show the structure during load-lowering operations.

Referring more particularly to the drawings, the structure illustrated comprises an upstanding circular shaft 10, partially broken away, as illustrated in Fig. 1, carried in any suitable manner on a base 11 which is adapted to rest upon the ground or other supporting surface. A main lifting body or frame 12 is mounted for longitudinal sliding movement along the shaft 10 to effect load-raising or lowering movements, the raising or lowering of the lifting body being under the control of friction clamp or cam operating mechanism, presently to be described.

The main lifting body 12 may conveniently be formed as a one-piece casting provided with a central bore through which the shaft 10 is adapted to project. The upper end of the lifting body is provided with a cylindrical or sleeve portion 13 adapted to support a rotatable load-engaging collar 14. The load-engaging collar is provided with a laterally projecting seat portion 15 adapted to be brought into engagement with the load to be raised, which may, for example, be the bumper of an automotive vehicle as illustrated by the reference numeral 16. While the lifting jack illustrated is thus of the automobile bumper jack type, it is to be understood that the principles of the invention may be adapted to lifting jacks and related structures of other types and kinds, and adapted for other purposes. The lower edge of the load-engaging collar is arranged to seat upon an annular bead 17 formed on the lifting body, and the cylindrical sleeve portion 13 is formed at its upper end with a projection 18 adapted to

45 prevent the inadvertent dislodgment of the load—
 50
 55

engaging collar in the event that the jack structure is inverted, as when not in use.

As shown, for example in Fig. 9, the lower end of the bore of the lifting body sleeve 13 is provided with a portion 19 of reduced diameter. The bore section 19 is adapted to cooperate with struck-out projections 28 formed on the upper end of the shaft 10 to prevent the projection of the lifting body upwardly off of the end of the shaft. The projections however may be received within the bore portion 21 of the sleeve as the lifting body is raised, whereby to increase the effective height of the jack.

The lifting body 12 is provided with a chamber 25 adapted to receive an auxiliary frame 26 and the associated jack operating mechanism. The auxiliary frame is also provided with a central bore through which the shaft 10 projects and is somewhat less in length than the vertical height of the chamber 25 whereby to permit the auxiliary frame to move vertically within the chamber with respect to the main lifting body. A compression spring 27 encircling the shaft 10 and arranged between the upper wall of the chamber 25 and the upper wall 28 of the auxiliary frame urges the frame downwardly into the position illustrated in Fig. 3. A conditioning or control lever 29 is pivotally mounted upon the lower wall of the lifting body by means of a screw 30. This lever is provided with an operating portion 31 adapted to engage the lower wall 32 of the auxiliary frame and force it upwardly against the action of the compression spring 27. When the control lever is in the position illustrated in Fig. 2, with the auxiliary frame held upwardly in the chamber 25, the structure is conditioned for load-raising operations. When the control lever is moved to its Fig. 3 position, the structure is conditioned for load-lowering operations.

The auxiliary frame is provided with a centrally disposed barrier wall 35 forming within the frame an upper chamber 36 and a lower chamber 37. The upper chamber is adapted to receive a holding clamp or cam 38 provided with a bore adapted to receive the shaft 10. The lower chamber 37 receives an actuating clamp assembly 39 also mounted upon the shaft 10. The holding clamp is preferably of one-piece construction, as illustrated, the bore of the clamp being cut away to bring the biting clamp edges 40 and 41 thereof into close horizontal disposition. The actuating clamp assembly is preferably composed of a plurality of laminated plates, as shown.

The holding clamp 38 is provided with a radially extending projection 42 adapted to be received within an opening 43 formed in the lifting body and an opening 44 formed in the auxiliary frame. The upper and lower shoulders or edges 45 and 46 of the lifting body opening are adapted to engage the clamp projection, thus controlling the operation of the clamp hereinafter to be described. The auxiliary frame opening 44 is of greater vertical extent than the opening 43. It merely provides clearance for the clamp projection and its edges do not operatively engage therewith.

A coil spring 50 is arranged between the barrier wall 35 and the holding clamp, encircling the shaft 10. The ends of the spring 50 are anchored into the barrier wall as best shown at 51 and 52 in Fig. 5. A compression spring 53 encircles the shaft 10 within the chamber 37 and bears between the actuating clamp assembly and the lower wall 32 of the auxiliary frame. The spring 75

53 constantly urges the actuating clamp 39 upwardly into engagement with the barrier wall 35, as illustrated in Fig. 9. The spring 50, during certain phases of the operation, engages the holding clamp, whereas in other phases of the operation the spring is out of contact with the clamp, as will be later described.

An operating lever 55 is pivotally mounted upon the lifting body, on a pivot pin 56, the pivot pin being carried by a pair of projecting ears 57 and 58, Fig. 4, formed on the lifting body. As best shown in Fig. 8, the operating lever is of tubular construction and adapted to receive an extension bar 59, preferably removable. The bar 59 may be of any suitable length to provide the necessary leverage in the operation of the lever. The operating lever is provided with a cross-shaft 60 which is adapted to engage the upper face of the extension portions 61 of the actuating clamp plates. The operating lever is also provided with a pair of projections 62 and 63 adapted to engage the lower face of the plate extensions.

In the operation of the structure, the base 11 is first suitably placed upon the support structure, and the control lever 29 adjusted to the position shown in Fig. 2 to condition the structure for load-raising operations. When the lever 29 is moved to its Fig. 2 position, it automatically stays in such position due to the fact that the downward thrust of spring 27 passes substantially through the lever axis 30. The lever is thus rendered self-locking. The lifting body 12 may then be pushed upwardly along the shaft 10 into engagement with the load, the load-engaging collar 14 first being rotated into proper load-engaging position. Upon adjustment of the control lever 29 to its Fig. 2 position, the auxiliary frame 26 is thrust upwardly against the action of compression spring 27, as seen in Figs. 2 and 9, causing the spring 50 to be brought into engagement with the lower face of the holding clamp 38. This causes the clamp to be urged or canted counterclockwise, as seen in Fig. 9, into holding or shaft-gripping position. This position of the clamp will hereinafter be referred to as its canted position as distinguished from its uncanted or release position. This terminology has reference to the operative relation between the clamp and the shaft and has no reference to horizontal or inclined position. In this position of the holding clamp upward movement of the lifting body 12 is permitted, but any retrograde movement is prevented. Attempted retrograde movement causes the shoulder 45 of the lifting body to engage the projection 42 of the holding clamp further tending to cant the clamp or cause it to grip the shaft. The compression spring 53 normally seats the actuating clamp assembly 39 against the baffle wall 35 in inoperative or uncanted position, as seen in Fig. 9. Accordingly with the parts conditioned as shown in Figs. 2 and 9, the lifting body may be manually forced upwardly along the shaft 10 into engagement with the load, neither the holding clamp nor the actuating clamp interfering with this movement of the lifting body.

The lifting body may then be further moved upwardly along the shaft to raise the load by manipulation of the operating lever 55. The action of the operating mechanism during lifting operations will best be understood by reference to Figs. 9 and 10. As the operating lever is pulled upwardly, or pivoted counterclockwise, as seen in Figs. 9 and 10, the cross-shaft 60 engages the actuating clamp canting it clockwise into grip-

ping engagement with the shaft 10, against the action of the spring 53. The actuating clamp thereupon acts as a reaction base for the shaft 60, so that upon further movement of the operating lever 55 the lifting body 12 will be raised by means of the pivotal connection 56 between the lifting body and the operating lever. During this upward movement of the lifting body, the control member 29 causes the auxiliary frame 26 to move upwardly as a unit therewith. Accordingly the spring 50 is maintained in continuous engagement with the holding clamp 38 maintaining it in canted or locking position. The holding clamp in such position may move upwardly along the shaft 10, but retrograde or downward movement of the clamp or lifting body with respect to the shaft is prevented. The position of the parts at the end of the upper stroke of the operating lever is shown in Fig. 10. As the operating lever is now moved downwardly or restored to normal position, the holding clamp prevents downward movement of the lifting body, and the actuating clamp is moved upwardly along the shaft 10 and restored to its normal Fig. 9 position. The compression spring 53 restores the actuating clamp, and in the event that the clamp should tend to stick, the projections 62 and 63 on the operating lever will engage and positively release the clamp. This operation may be repeated to raise the load step by step the desired amount.

The load-lowering operations will be best understood with reference to Figs. 11, 12, 13 and 14. To effect lowering movements, the control lever 29 is first released to its Fig. 3 position, permitting the compression spring 27 to force the auxiliary frame 26 downwardly, causing the lower wall 32 of the frame to seat against the lower wall of the lifting body chamber 25. This causes the spring 50 to move away from the holding clamp 38, but due to the fact that the holding clamp is already in canted or holding position, the weight of the load on the clamp, by reason of the contact between the lifting body shoulder 45 and the clamp projection 42, maintains the clamp in canted or holding position. The operating lever 55, which is now in its Fig. 11 position, is then moved upwardly or counterclockwise to again bring the shaft 60 into engagement with the actuating clamp 39. The engagement between the operating lever and the actuating clamp causes the clamp to be canted into gripping engagement with the shaft, serving as a reaction base and resulting in the slight raising of the lifting body as the operating lever is raised. As the lifting body shoulder 45 is lifted away from the holding clamp, the clamp falls by gravity into its uncanted or release position, Fig. 12; or alternatively in the event the holding clamp should tend to stick in holding position, the lower lifting body shoulder 46 will engage the clamp projection 42, as illustrated in Fig. 12, positively moving the clamp to its release position. While the holding clamp is now released, it is to be noted that the actuating clamp is in active or gripping position, thus serving as a support means for the lifting body and the load through the intermediary of the operating lever and the pivot connection 56.

As the operating lever is now moved downwardly, or clockwise, the lifting body will be lowered. As the movement progresses the actuating clamp, which is locked to the shaft 10, will become engaged against the barrier wall 35, as indicated at the point 65 in Fig. 13, thus hold-

ing the auxiliary frame 26 from further downward movement. Inasmuch as the auxiliary frame is held from further downward movement whereas the lifting body 12 will continue to move downwardly with the operating lever, separation between the lifting body and auxiliary frame takes place as shown in Fig. 13, overcoming the action of the compression spring 27. The holding clamp 38 moves downwardly with the lifting body, whereas the spring 50 is held stationary with the auxiliary frame. Accordingly as the movement progresses the spring engages the clamp and ultimately again cant it into locking position. This position of the parts is shown in Fig. 13, just prior to the time of engagement between the holding clamp projection 42 and the lifting body shoulder 45. It is to be noted that the contact 65 between the actuating clamp and the barrier wall of the auxiliary frame tends to move the actuating clamp into released or uncanted position. However, the force of the spring 27 which determines the force of contact at this point is insufficient to overcome the force of the load which maintains the clamp in canted position. In other words, during the lowering motion of the lifting body just described, the entire weight of the load is carried by the actuating clamp at its point of contact with the shaft 60 of the operating lever, and this contact insures the maintenance of the actuating clamp in shaft-gripping position.

When the lowering movement progresses to the point indicated in Fig. 14, wherein the shoulder 45 of the lifting body engages the holding clamp, the lifting body becomes supported by the holding clamp. As this engagement occurs further downward or clockwise movement of the operating lever 55 causes a release of the pressure engagement between the shaft 60 and the actuating clamp. Immediately as this takes place the actuating clamp is released from the shaft, and the compression spring 27 thrusts the auxiliary frame downwardly, the parts assuming the position illustrated in Fig. 14. The actuating clamp is released, but the holding clamp is now in canted or load-supporting position, and due to the fact that it is the assumption of the load by the holding clamp which causes the release of the actuating clamp it is insured that at least one of the clamps will always be in control of the load. To effect further lowering of the load, the operating lever is again raised as illustrated in Fig. 12 to cant the actuating clamp into gripping engagement with the shaft and the cycle of operation is repeated.

The structure provides a lifting jack of the friction gripping clamp or cam type wherein both the load-raising and load-lowering operations may be effected from a single operated lever in step by step fashion or in predetermined increments of movement. The mechanism is conditioned for load-raising or load-lowering merely by the proper positioning of the control lever 29. The movements of the lifting body both upwardly and downwardly are controlled at all times, at least one of the gripping clamps being continuously operable to support and control the load. Uniformity and safety of operation is assured.

It is obvious that various changes may be made in the specific embodiment of the invention set forth for purposes of illustration without departing from the spirit thereof. Accordingly the invention is not to be limited to the specific em-

bodiment set forth, but only as indicated in the following claims.

The invention is hereby claimed as follows:

1. A lifting jack comprising a base, a load-engaging member, means for moving the load-engaging member relative to the base comprising a pair of friction clamps, one of said clamps being an actuating clamp and the other of the clamps being a holding clamp, an operating member for controlling the movements of the clamps, a spring engageable with the holding clamp, and means for maintaining the spring in constant engagement with the holding clamp during movement of the load-engaging member in one direction with respect to the base and for causing the spring to alternately engage and disengage the holding clamp as the load-engaging member is moved in the opposite direction with respect to the base.

2. A lifting jack comprising a base, an up-standing shaft mounted on the base, a lifting body including a load-engaging member longitudinally movable on the shaft, means for moving the lifting body along the shaft comprising a pair of friction clamps, one of said clamps being an actuating clamp and the other of the clamps being a holding clamp, an operating member for controlling the movements of the clamps, a spring engageable with the holding clamp, and means for maintaining the spring in constant engagement with the holding clamp during movement of the lifting body in one direction along the shaft, and for causing the spring to alternately engage and disengage the holding clamp during movement of the lifting body in the opposite direction along the shaft.

3. A lifting jack comprising a base, a load-engaging member, means for moving the load-engaging member relative to the base comprising a housing and a pair of friction clamps associated therewith, one of said clamps being an actuating clamp and the other of the clamps being a holding clamp, an operating lever pivoted to the housing for controlling the movements of the clamps, a frame carried by the housing, a control lever for shifting the frame relative to the housing, and a spring controlled by the position of the frame and engageable with the holding clamp, the spring being in constant engagement with the clamp when the frame is in one position of adjustment as the load-engaging member is moved in one direction with respect to the base, and the spring being alternately engageable and disengageable with the holding clamp when the frame is in another position of adjustment as the load-engaging member is moved in the opposite direction with respect to the base.

4. A lifting jack comprising a base, a load-engaging member, means for moving the load-engaging member relative to the base comprising a housing and a pair of friction clamps associated therewith, one of said clamps being an actuating clamp and the other of the clamps being a holding clamp, an operating lever pivoted to the housing for controlling the movements of the clamps, a control lever pivoted to the housing, a frame shiftably mounted within the housing, a spring for urging the frame into one position with respect to the housing, said control lever being operable to shift the frame to another position of adjustment within the housing, and a spring engageable with the holding clamp, said last named spring being constantly engageable with the clamp when the frame is in one position of adjustment as the load-engag-

ing member is moved in one direction with respect to the base, and being alternately engageable and disengageable with the clamp when the frame is in another position of adjustment as the load-engaging member is moved in the opposite direction with respect to the base.

5. A lifting jack comprising a base, a load-engaging member, means for moving the load-engaging member relative to the base comprising a pair of friction clamps, one of said clamps being an actuating clamp and the other of the clamps being a holding clamp, an operating member for controlling the movements of the clamps, an actuating clamp spring engageable with the actuating clamp for moving it into inoperative position, said actuating clamp spring being constantly engageable with the actuating clamp, and a holding clamp spring engageable with the holding clamp for moving it to operative position, said holding clamp spring being constantly in engagement with the holding clamp as the load-engaging member is moved in one direction of movement, and means operable as the load-engaging member is moved in the opposite direction of movement for relatively shifting the holding clamp spring and the holding clamp toward and from each other whereby to bring them alternately into engagement and disengagement.

6. A lifting jack comprising a base, a load-engaging member, means for moving the load-engaging member relative to the base comprising a pair of friction clamps, one of said clamps being an actuating clamp and the other of the clamps being a holding clamp, an operating member for controlling the movements of the clamps, an actuating clamp spring constantly engageable against the actuating clamp, a holding clamp spring, and means for moving the holding clamp spring relatively toward and away from the holding clamp whereby to cause said spring and clamp to become alternately engaged and disengaged.

7. A lifting jack comprising a base, a load-engaging member, means for moving the load-engaging member relative to the base comprising a friction clamp, an operating member for controlling the movements of said clamp, a spring engageable with the clamp, and means for moving the spring and clamp relatively toward and away from each other as the operating member is actuated whereby to cause the spring and clamp to become alternately engaged and disengaged.

8. A lifting jack comprising a base, a load-engaging member, means for moving the load-engaging member relative to the base comprising a pair of friction clamps, one of said clamps being a single piece clamp and the other of said clamps being of laminated construction, and an operating member for controlling the movements of said clamps.

9. A lifting jack comprising a base, a load-engaging member, means for moving the load-engaging member relative to the base comprising a housing and a pair of friction clamps associated therewith, one of said clamps being a single piece holding clamp and the other of said clamps being a laminated actuating clamp, and an operating lever for controlling the movements of said clamps, said operating lever being directly engageable with the laminated actuating clamp.

10. A lifting jack comprising a base, a load-engaging member, means for moving the load-

engaging member relative to the base comprising a housing and a pair of friction clamps associated therewith, one of said clamps being an actuating clamp and the other of the clamps being a holding clamp, an operating lever pivoted to the housing and engageable with the actuating clamp, a baffle wall operatively associated with the housing, a spring for normally urging the actuating clamp into inoperative position against said wall, a fulcrum formed on the housing against which the holding clamp is adapted to engage, a spring supported by said baffle wall for urging the holding clamp into operative position against said fulcrum, and means for shifting the baffle wall within the housing for moving the last named spring into engagement with the holding clamp.

11. A lifting jack comprising a base, an up-standing shaft mounted on the base, a lifting body including a load-engaging member longitudinally movable on the shaft, means for moving the lifting body along the shaft comprising a pair of friction clamps, one of said clamps being an actuating clamp and the other of the clamps being a holding clamp, an operating lever pivoted to the lifting body engageable with the actuating clamp, a baffle wall operatively associated with the lifting body, a spring for urging the actuating clamp into inoperative position against said wall, a fulcrum formed on the lifting body against which the holding clamp is adapted to be operatively engaged, a spring supported by said baffle wall engageable with the holding clamp for urging it into operative position against said fulcrum, and means for shifting the baffle wall within the lifting body for moving said last named spring into operative engagement with the holding clamp.

12. A lifting jack comprising a base, a load-engaging member, and means for moving the load-engaging member relative to the base comprising a shaft, a housing, a pair of friction clamps associated with the housing and mounted on the shaft, one of said clamps being an actuating clamp and the other of the clamps being a holding clamp, an operating lever pivoted to the housing for operating the clamps, said operating lever having operating connection with the clamps to move the load-engaging member in step by step increments of movement both upwardly and downwardly with respect to the base upon lever operation, and control mechanism operatively associated with the clamps for controlling the manner of movement of the clamps upon operation of the lever, said control mechanism comprising a frame shiftably mounted on the housing and operatively connected with the holding clamp for controlling the operation thereof, and means including a manually adjustable control handle and said operating lever for controlling the shifting of the frame.

13. A lifting jack comprising a base, a load-engaging member, and means for moving the load-engaging member relative to the base comprising a shaft, a housing, a pair of friction clamps associated with the housing and mounted on the shaft, one of said clamps being an actuating clamp and the other of the clamps being a holding clamp, an operating lever pivoted to the

housing for operating the clamps, said operating lever having operating connection with the clamps to move the load-engaging member in step by step increments of movement both upwardly and downwardly with respect to the base upon lever operation, and control mechanism operatively associated with the clamps for controlling the manner of movement of the clamps upon operation of the lever, said control mechanism comprising a frame shiftably mounted on the housing and operatively connected with the holding clamp for controlling the operation thereof, and means including a manually adjustable control handle and a spring for controlling the shifting of the frame.

14. A lifting jack comprising a base, a load-engaging member, and means for moving the load-engaging member relative to the base comprising a shaft, a housing, a pair of friction clamps associated with the housing and mounted on the shaft, one of said clamps being an actuating clamp and the other of the clamps being a holding clamp, an operating lever pivoted to the housing for operating the clamps, said operating lever having operating connection with the clamps to move the load-engaging member in step by step increments of movement both upwardly and downwardly with respect to the base upon lever operation, and control mechanism operatively associated with the clamps for controlling the manner of movement of the clamps upon operation of the lever, said control mechanism comprising a selectively adjustable manual control handle and a coiled spring encircling the shaft and operatively engageable with the actuating clamp.

15. A lifting jack comprising a base, a load-engaging member, and means for moving the load-engaging member relative to the base comprising a shaft, a housing, a pair of friction clamps associated with the housing and mounted on the shaft, one of said clamps being an actuating clamp and the other of the clamps being a holding clamp, an operating lever pivoted to the housing for operating the clamps, said operating lever having operating connection with the clamps to move the load-engaging member in step by step increments of movement both upwardly and downwardly with respect to the base upon lever operation, and control mechanism operatively associated with the clamps for controlling the manner of movement of the clamps upon operation of the lever, said control mechanism comprising a selectively adjustable manual control handle, a holding clamp spring positioned by said control handle and adapted to operatively engage the holding clamp, and an actuating clamp spring encircling the shaft and adapted to engage the actuating clamp for controlling the operation thereof.

16. A lifting jack as defined in claim 15 wherein the holding clamp is disposed on the shaft above the actuating clamp, wherein the holding clamp spring is arranged between the holding clamp and the actuating clamp, and wherein the actuating clamp spring is disposed below the actuating clamp and engageable with the lower surface thereof.

MILLARD B. LUCKER.
